UNITED STATES PATENT OFFICE.

PETER R. SHIRK AND FREMONT W. SHIRK, OF EPHRATA, PENNSYLVANIA.

CUTTER.

Application filed March 19, 1921. Serial No. 453,558.

To all whom it may concern:

Be it known that we, PETER R. SHIRK and FREMONT W. SHIRK, citizens of the United States, residing at Ephrata, in the county of 5 Lancaster and State of Pennsylvania, have invented new and useful Improvements in Cutters, of which the following is a specification.

This invention relates to the revolving reversible thimble for a cigar cutter, the principal object of the invention being to provide means for smoothing the head of a cigar while the tuck is being cut off.

Another object of the invention is to provide means whereby the thimble can be rotated in either direction so that it can be used on a cigar which has been wrapped in a right or left hand direction.

This invention also consists in certain 20 other features of construction and in the combination and arrangement of the several parts, to be hereinafter fully described, illustrated in the accompanying drawings and specifically pointed out in the appended 25 claims.

In describing our invention in detail, reference will be had to the accompanying drawings wherein like characters denote like or corresponding parts throughout the several 30 views, and in which:—

Figure 1 is a plan view of the invention. Figure 2 is a longitudinal sectional view.

Figure 3 is a view looking towards one end of the apparatus.

Figure 4 is a view looking towards the other end.

Figure 5 is a section on line 5—5 of Figure 1.

In these views 1 indicates a casing, the top 40 of which is provided with a longitudinal groove 2 and the end 3 of which is provided with a recess 4 which is designed to act as one part of the cutting means. A shaft 5 is rotatably mounted in the casing and this 45 shaft passes through one end of the casing and this projecting end has secured thereto a knife 6 which cooperates with the recess 4 to cut the tuck off. A spring 7 is secured to this shaft and a part of the casing and acts 50 to return the knife to raised position.

The end of the casing opposite the knife carrying end is provided with an upwardly projecting extension in which is journaled the shaft 9. A frame 10 is secured to said 55 shaft within the extension and a thimble 11 is also secured to that part of the shaft

which projects from the inner side of the extension. This thimble is located above the groove 2. An arcuate slot 12 is formed in the end of the casing and a rod 13, secured to the frame 10, extends through said slot and has its end screw threaded to receive the thumb nut 14. By this means the frame can be adjusted on shaft 9. The frame carries a pair of gears 15 and 15' which mesh with the pinion 16 on shaft 9. A train of gears 17 are arranged within the casing, one of these gears 17' being arranged on shaft 5 and is connected to said shaft by the ratchet mechanism 18.

The parts are so arranged that when the knife 6 is depressed to cut the tuck off the cigar which has been placed in the groove 2 in the casing with its head in the thimble and its tuck end in the recess 4, the rotation of shaft 5 will, through the ratchet mechanism, the gears 17 and 17' and the gear 15 or 15' cause shaft 9 to rotate through pinion 16 and thus the thimble will be rotated to smooth the head of the cigar. When the knife is released after the cutting operation the spring will return the shaft 5 and said knife to normal position but the thimble will not be rotated in this retrograde position due to the ratchet mechanism.

If the cigar has been wrapped in an opposite direction the thimble must be rotated in this direction and to secure this rotation of the thimble it is simply necessary to tilt the gear frame 10 by means of the rod 13 90 and its nut 14 working in the slot 12 to bring the other gear 15 or 15' into engagement with one of the gears 17.

From the above it will be seen that the head of the cigar is operated upon by the 95 thimble while the tuck is being cut off and that the device can be made to operate upon cigars which have the right hand wrap or left hand wrap.

It is thought from the foregoing description that the advantages and novel features 100 of our invention will be readily apparent.

We desire it to be understood that we may make changes in the construction and in the combination and arrangement of the several 105 parts, provided that such changes fall within the scope of the appended claims.

What we claim is:

1. A device of the class described comprising a casing, cutting means thereon, a 110 thimble for engaging the head of the cigar, means for revolving the thimble by the ac-

tion of the cutting means, such means including means for reversing the rotation of the thimble when desired.

2. A device of the class described comprising a casing, cutting means at one end thereof, a thimble at the other end, means for rotating the thimble by the cutting action of the cutting means, such means including means for reversing the rotation of the thimble when desired and means for returning the cutting means to normal position without rotating the thimble.

3. An apparatus of the class described comprising a casing, a shaft journaled therein and having a part projecting from one end of the casing, a knife connected with said projecting end, spring means connected with the shaft for holding the knife in raised position, a thimble at the other end of the casing, gearing connecting the thimble with the shaft, ratchet mechanism associated with the gearing for actuating the thimble on the cutting movement of the knife but permitting

the spindle to remain idle when the spring returns the knife to normal position.

4. An apparatus of the class described comprising a casing, a shaft journaled therein and having a part projecting from one end of the casing, a knife connected with said projecting end, spring means connected with the shaft for holding the knife in raised position, a thimble at the other end of the casing, gearing connecting the thimble with the shaft, ratchet mechanism associated with the gearing for actuating the thimble on the cutting movement of the knife but permitting the spindle to remain idle when the spring returns the knife to normal position and means for changing the position of the gearing for reversing the direction of movement of the thimble when desired.

In testimony whereof we affix our signatures.

PETER R. SHIRK.
FREMONT W. SHIRK.
